Primary Examiner—Stacia Cadmus(74) *Attorney, Agent, or Firm*—Greer, Burns & Crain, Ltd.(57) **CLAIM**

The ornamental design for an automobile tire, as shown and described.

DESCRIPTION

FIG. 1 is a front view of the automobile tire, showing the new design, a top plan view and a bottom plan view thereof appearing the same as the front view;

FIG. 2 is a rear view of the automobile tire;

FIG. 3 is a left side view of the automobile tire;

FIG. 4 is a right side view of the automobile tire;

FIG. 5 is a fragmentary front view, showing in enlargement the portion of 5—5 in FIG. 1;

FIG. 6 is a cross-sectional view, taken on line 6—6 in FIG. 5; and,

FIG. 7 is a perspective view of the automobile tire.

In the drawings, the broken lines represent environmental structure only and form no part of the claimed design; the claimed design being the tread pattern shown by solid lines, up to the peripheral boundary between the tread and the sidewall of the article, represented by dash-dotted lines. A top plan view and a bottom plan view appears the same as the front view.
